UNITED STATES PATENT OFFICE.

WILLIAM CALOWAY MEADOWS, OF MORAVIAN FALLS, NORTH CAROLINA.

TURBINE WATER-WHEEL.

SPECIFICATION forming part of Letters Patent No. 415,842, dated November 26, 1889.

Application filed May 11, 1889. Serial No. 310,419. (No model.)

To all whom it may concern:

Be it known that I, WILLIAM CALOWAY MEADOWS, a citizen of the United States, residing at Moravian Falls, in the county of 5 Wilkes and State of North Carolina, have invented certain new and useful Improvements in Turbine Water-Wheels; and I do declare the following to be a full, clear, and exact description of the invention, such as will enable 10 others skilled in the art to which it appertains to make and use the same, reference being had to the accompanying drawings, and to the letters and figures of reference marked thereon, which form a part of this specification.

15 The special object of my invention is to construct the bucket of a turbine water-wheel so as to utilize the water-power as much as possible.

Figure 1 of the drawings is a perspective 20 view of the wheel without the casing; Fig. 2, a horizontal section thereof, and Fig. 3 a detail perspective view of the bucket-piece adjacent to the hub.

In the drawings, A represents a water-wheel, which is preferably, but not necessarily, made with a hub H.

I make the upper part B of my bucket with a face 1 inclining forward toward the bottom and slightly concaved. Flush with this face 30 is the edge face 2 on a piece b', placed at angle to piece b and parallel to the periphery of the wheel. b² is a piece which connects piece b' with the hub H and has face 3 curved rearwardly upward to force the water down into the deep cavity b³, where it collects in a solid column and acts propulsively with great effect. The piece b² extends down into the lower part B' of the bucket, where it curves outwardly to the discharge-opening, while the 40 bottom b⁴ and side b⁵ combine with it to form a cavity b⁶, which widens or flares toward the rear.

D is a partition-ring, which divides the two parts B B' of my wheel, and E is the plate 45 which covers the top of wheel. The buckets are attached in any preferred way to the pieces D E. Between the ring D and the hub H a suitable opening is left unoccupied by the buckets.

The operation is as follows: The water first 50 strikes the outer face 1, then collects in a heavy column in the cavity b³ between the hub and the bucket-piece b' in consequence of the upper rearward curve of face 3, thence it flows into the cavity b⁶ of the lower part of 55 my bucket, where the steep rearward curve of the lower end of face 3 and the gradual widening of the cavity b⁶ cause a free discharge of the water.

I am well acquainted with the turbine 60 water-wheel described in Patent No. 183,828, which has an outward discharge, and also with others which have a downward discharge; but the object of my construction is to combine the two, so as more fully to utilize the 65 power of the water and thus greatly increase the useful effect. The upper part of my bucket, with its three faces numbered 1 2 3, is entirely unlike the plain surface shown in the corresponding part of the bucket described in Patent No. 183,828, which has the water-way narrowed so as to clog and impede the incoming water, thus deadening its action. On the other hand, my bucket widens 70 as the water goes to allow a free action and discharge, the velocity of the water being gradually checked by the curves of the bucket. As the volume of the water increases in its progress through the wheel, it requires a 75 larger opening for the discharge than for the entrance, or the wheel would be clogged; hence,

What I claim as new, and desire to protect by Letters Patent, is—

In a turbine wheel, the combination, with a 80 ring D and hub H, of an upper part B, having the beveled slightly-concaved face 1, the face 2, parallel to the periphery of wheel, and the face 3, starting at top even with the face 1, curving forward in front of face 2 and covering the space between the face 2 and the 85 said hub, as and for the purpose described.

In testimony whereof I affix my signature in presence of two witnesses.

WILLIAM CALOWAY MEADOWS.
